(Cl. D3—13)

To all whom it may concern:

Be it known that we, Paul M. Maxwell and Klári M. Wlach, each a citizen of the United States, residing respectively, at Milton, county of Ulster, and State of New York, and at New York, county of New York, and State of New York, have invented a new, original, and ornamental Design for Hats, of which the following is a specification, reference being had to the accompanying drawing, forming part thereof.

Fig. 2 is a view of the other side of the hat.

Fig. 3 is a top view thereof.

Fig. 4 is a front view thereof.

We claim:

The ornamental design for a hat, as shown.

PAUL M. MAXWELL.
KLÁRI M. WLACH.
